LIGHTING DEVICE

Chester H. Braselton, New York, N. Y., assignor,
by mesne assignments, to Sirian Wire and Contact Company, Newark, N. J., a corporation of Delaware

Application October 15, 1930, Serial No. 488,733

17 Claims. (Cl. 176—122)

This invention relates to electric lamps and particularly to that type of lamp which makes use of the passage of an electronic stream through space for its operation.

One of the objects of the invention is to provide a lamp in which a refractory body is bombarded by a stream of directed and controlled electrons.

Another object of the invention is to provide an electric lamp in which a cathode surface is heated to electron emitting temperature in the presence of an ionized gas and bombards a refractory body heating it to incandescence by said bombardment.

Another object of the invention is to provide an electric lamp in which the temperature of the light giving element is raised to a higher point than possible where such element carries the current for operating the lamp.

Other objects of the invention and objects relating particularly to the method of constructing and assembling the various parts will be apparent as the description of the invention proceeds.

Several embodiments of the invention have been illustrated in the accompanying drawings in which:

Fig. 1 is a side elevational view partly in section of one form of the lamp which may be preferred;

Fig. 2 is a longitudinal sectional view of a modified form of the cathode of Fig. 1;

Fig. 3 is a side elevational view partly in section of a modified form of the elements of the lamp;

Fig. 4 is a side elevation of a lamp illustrating a still further modification;

Fig. 5 is a side elevation of another modification of the invention;

Figs. 6 and 7 are modified forms of the inner coils shown in the construction of Fig. 5;

Fig. 8 is an elevation of a still further modification of the invention;

Fig. 9 is an enlargement of the upper end of the construction of Fig. 8;

Fig. 10 is an elevation showing another embodiment of the invention;

Fig. 11 is an elevation showing a still further modified form of the invention;

Fig. 12 is a longitudinal sectional view of a modified form of the construction shown in Fig. 11; and

Fig. 13 is an elevation of still another modified form of the invention.

Referring now more specifically to Fig. 1 the 55

invention is shown as comprising an envelope 10 having the usual press 11 formed integral therewith and for the purpose of supporting the various elements. A cathode 12, preferably formed as a cylindrical shell out of a refractory metal such as tungsten, molybdenum, tantalum, or nichrome, may be supported by means of a short connecting rod 13 which may be welded to a support rod 14 sealed in the press 11. The cathode 12 may be filled with an insulating material 15 which may be any suitable material capable of standing a high temperature and permitting degasification. A filamentary resistance wire 16 may be embedded in the insulating material 15 with its lower end connected to the support rod 14 and its upper end connected to a support rod 17 which may be bent outwardly and downwardly, extending substantially parallel to the cathode but spaced therefrom and sealed in the press 11. The cathode cylinder may also be coated with electron emitting material 18 which may be any of the well known materials used for that purpose, such as the oxides of the alkali earth metal group or mixtures of such oxides held together upon the cathode with a suitable binder.

A coil 19 of refractory wire, preferably tungsten, may be placed around the cathode 12 but having a large enough diameter to be spaced therefrom and the upper end of this coil may be connected to the support rod 17 while the lower end may be connected to a third support rod 20 which may be sealed in the press 11.

The envelope 10 may be filled with an ionizable gas, preferably one of the monatomic gases, such as neon, argon, helium, krypton, or xenon, or mixtures of such gases, at a pressure of in the neighborhood of 200 mm. of mercury. A trace of a metal vapor or vapors may be added to the gas if desired for color effects or to increase the conductivity thereof. These vapors may be vapors of mercury, calcium, caesium, rubidium, or cadmium.

The metal-vapors may be introduced into the bulb by providing a container 21 formed in the usual manner of a pressed metal cup and supported by means of a wire 22 upon one of the support rods, as the rod 17 in Fig. 1. A small quantity of a salt of the metal, such as the chloride thereof, may be placed in the container 21 with a small piece of calcium or magnesium and when the container 21 is heated to a high enough temperature the calcium or magnesium will combine with the chloride of the metal forming calcium or magnesium chloride and liberating the free metal which will condense on the walls of

the bulb and other parts to be vaporized again when heated in use.

Lead-in wires 23 and 24 may be connected respectively to the support rods 11 and 14 for making the oxide connections to the bulb.

With the parts assembled as shown in Fig. 1 the envelope 10 may be connected to an exhaust pump and an oven placed over it to raise the temperature of the entire lamp to between 350 and 400° C. A current may be run through the filament at this time to heat it slightly so as to expel the gases therein and the pump then withdraws the gases as they are liberated. When no more gases are apparent in the bulb as is evidenced by a lack of fluorescence when high tension current is directed against the walls of the bulb from an induction coil, the current through the filament may be increased to raise the temperature thereof to approximately 800° C. to drive out the binder from the electron emitting material on the outer surface of the cathode and other occluded gases which may be present. When no more gases are again found in the bulb the oven may be raised and the filament current increased to raise the temperature to slightly less than 1200° C., the pump being connected all this time to remove the gases driven off.

When no more gases appear in the bulb the filament current may be turned off and the pump disconnected and a slight amount of an inert gas, such as neon, having a pressure of about .5 mm. admitted to the bulb and the filament current turned on again and increased gradually. Spots of localized discharge will then appear on the parts of the bulb and will gradually spread until a diffused glow completely fills the bulb. This appears to activate the electron emitting material and the process should be continued until the glow completely fills the bulb which should take less than ten minutes.

If white discharge spots appear on the cathode or other parts of the light it is an indication that there are more vapors or gases within the bulb and the pump should be again connected and the gases withdrawn and the process of activation repeated.

When the activation is completed the filament current may be raised for a moment to approximately 1400° C. and the gases pumped out again to remove any undesirable gases which may have been driven off during the activation process. At this time a high vacuum of in the neighborhood of .5 micron is preferably obtained. The vacuum pump may then be shut off and the filament current turned off and about 50 mm. of neon and 150 mm. of argon admitted into the bulb after which the bulb may be sealed off.

If the metal vapors are to be introduced into the bulb as stated above the container 21 may be bombarded externally after sealing off to liberate the metal vapor or if the metal vapors are not used it may be desirable to flash some magnesium in the same manner to clean up the gases in the bulb.

When the bulb as described is connected across a light circuit current will flow through the lead-in wire 23, the support rod 17, the filament 16, the support 14, and will pass out through the lead-in wire 24. This will energize the filament 16 causing it to heat the insulation material and the cathode 12 and raise the temperature thereof until the electron emitting material reaches the emission temperature. Inasmuch as the cathode 12 is electrically connected by means of the rod 13 to the support rod 14 which forms

one side of the circuit, and the coil 19 is electrically connected to the rod 17 or to the opposite side of the circuit the potential between the coil 18 and the cathode 12 will be the line potential and a stream of electrons will therefore leave the cathode and bombard the coil 18 increasing the temperature thereof until it radiates light.

In Fig. 2 a modified form of the cathode is shown wherein a coil 12a of refractory metal is closely wound on the insulating core instead of a metal shell.

In Fig. 3 a cathode 25 similar to the cathode 12 of Fig. 1 and coated with electron emitting material 26 may be supported upon a rod 27 which is sealed in the press 11 by means of a strap 28 at its upper end and a strap 29 at its lower end. A hairpin coiled filament 30 may be embedded in the insulating material 31 which extends through the cathode 25 while the ends thereof may be connected at the lower end of the cathode to two support wires 32 and 33. A connector 34 may connect the rod 33 with the rod 27 so that the cathode is electrically connected to one side of the heating coil. A large coil 35 of refractory metal such as tungsten may be supported upon a rod 36 which may extend parallel with the cathode and be sealed in the press in the usual manner. The support rod 36 may be connected to the support rod 32 by means of a short support rod 37 so that the coil 35 is connected to the opposite side of the heater circuit. With this construction a greater resistance may be made per unit length of cathode inasmuch as two lengths of the coil extend through the cathode.

Inasmuch as the electrons move from a negative body to a more positive one the electron stream in the construction of Figs. 1 and 3 will operate only on one-half of an alternating current cycle and in order to make the lamp use both halves of the cycle the construction of Fig. 4 may be used. In this construction a pair of cathodes 38 and 39 are mounted in parallel relation and spaced from each other upon a central support rod 40 by means of straps 41 and 42 which pass around the upper and lower ends respectively of the cathodes and are welded to the support rod 40. A single coiled filament 43 may extend up through the cathode 38 and be attached to a connector 44 at the top thereof which may be welded to the upper end of the rod 40 and extend over the top of the cathode 39. Another single coiled filament 45 may extend through the cathode 39 being attached at its upper end to the connector 44. The lower ends of the filaments 43 and 45 may be connected respectively to support rods 46 and 47 which may be sealed in the press 11. The cylindrical cathodes 38 and 39 may be formed similarly to those already described and filled with an insulating material in which the filament 43 and 45 are embedded. A coil of heavy tungsten wire 48 may surround the cathode 38 while a coil 49 may surround the cathode 39 in a manner similarly to what has already been described. The upper and lower ends of the coil 48 may be supported upon a support rod 50 while the upper and lower ends of the coil 49 may be supported upon a support rod 51 as indicated. The coils should be made of heavy enough wire to maintain their position spaced from the cathodes 38 and 39.

In this construction it will be evident that the cathodes through the support rod 40 are connected to the midpoint of the double filament 43

and 45 and that the coils 48 and 49 are connected respectively to the opposite sides of the circuit.

Leading-in wires 52, 53, 54, and 55 may be connected respectively to support rods 50, 46, 47, and 51. The leading-in wires 52 and 53 may be connected together as shown and the leading-in wires 54 and 55 may also be connected together to connect the coils 48 and 49 to opposite sides of the circuit.

With this construction a potential difference between either cathode and its adjacent coil will be substantially one-half of the potential across the entire circuit and as both cathodes are connected to the midpoint of the filament the cathodes will always be negative with respect to one of the coils so that at least one coil will always be bombarded which produces a uniform effect throughout both halves of the cycle.

While the tubular cathodes as shown in the foregoing construction are indicated as being filled with insulating material in which the filament is embedded, it is also possible to support the filament within the cathode without any insulation material so that the cathode will heat by radiation only from the filament.

In Fig. 5 a further modification of the construction is shown. Here a plurality of coils 56 and 57 of relatively heavy refractory wire are mounted at their lower ends respectively upon support rods 58 and 59 which may be sealed in the press 60 and surrounded by the envelope 61. The coils 56 and 57 may have a relatively large diameter and the upper ends thereof may be bent inwardly to form supports for two smaller coils 62 and 63 which extend down through the center of the coils 56 and 57 and are attached to a cross connecting member 64 which in turn may be welded to a support rod 65 sealed in the press 60. Thus the small coils 62 and 63 are supported within the larger coils and spaced therefrom. Each of the coils 62 and 63 may be provided with a coating of electron emitting material which, as shown, is coated upon the individual turns of the coil.

Leading-in wires 66 and 67 may be connected respectively to support rods 58 and 59 so that when the lamp is connected across a lighting circuit the current flows through the leading-in wire 66, the support rod 58, the large diameter coil 56, the small coil 62, the connecting member 64, the small diameter coil 63, the larger diameter coil 57, the support rod 59, and out through the leading-in wire 67. This energizes all of the coils although the small diameter coils will heat up to a high temperature due to the higher resistance and as soon as these small diameter coils become heated to the electron emitting temperature electrons will bombard the outer coils and raise the temperature thereof so that they become refractory and emit intense illumination.

The small diameter coils 62 and 63 may if desired be coated with electron emitting material as indicated in Fig. 6 where the coil 68 is shown coated with electron emitting material 69, or the construction of Fig. 7 may be employed in which the coil 70 is provided with a core 71 of electron emitting material. The latter construction may be preferable inasmuch as the core inside of the coil helps to support it and will prevent it short circuiting against the outer coil. However, if desired, the filament itself may be made electron emitting by making it of thoriated tungsten which may be made by treating tungstic acid and thorium nitrate or a filament in which other

electron emitting materials have been intimately mixed with the metals may be used. Any of the constructions, however, will provide the same results in that the outer coils are bombarded by electrons and the temperature thereof raised to radiating temperature.

A somewhat different embodiment of the invention is shown in Fig. 8 in which a filamentary coil 72 of resistance wire is bent in the form of a V, or hairpin, having the ends thereof attached to two support rods 73 and 74 which may be sealed in the press 75 of the lamp. A center support rod 76 may have a tungsten or other refractory wire 77 welded to it which is provided at its upper end with a ring or loop 78 through which the filament 72 may extend to support the upper end of the filament. The wire 77 may be coated with electron emitting material 79 and in operation when this wire becomes heated it will emit electrons, inasmuch as it is attached to the midpoint of the filament, to the sides of the V filament which are left uncoated, thereby bombarding the filament and raising the filament to a higher degree than it is raised by the current passing therethrough.

In Fig. 10 a coil 80 of filamentary resistance wire is shown supported upon a rod 81 at the top and a rod 82 at the bottom thereof. This coil may be coated with electron emitting material in any of the manners already described. A rod 82 of refractory metal or other refractory material, such as carbon, may be supported at its upper end upon the rod 81 and at its lower end upon the support rod 83 provided for that purpose. The rod 82 is positioned substantially parallel to the axis of the coil 80 and as it is connected to one end thereof it will be bombarded by electrons from the coil, raising the temperature thereof to a radiating temperature and thereby emitting light.

In Fig. 11 a modification of this construction is shown in which the rod extends within the coil on the axis thereof. As shown, the rod 84 is attached to a support rod 85 which also forms the support rod for one end of the coil 86 the other end of which is attached to a support rod 87 which is, together with the rod 85, sealed in the press 88. The rod 84 is mounted on the axis of the coil 86 and may be coated with electron emitting material, if desired, to bombard the coil, or the coil itself may be coated with electron emitting material as indicated in Fig. 12 where the coil 89 is provided with electron emitting material 90 and the rod 91 extends inside of the coil. However where the rod extends in the center of the coil it may be preferred to coat the rod with the material rather than the coil as a coating upon the coil may tend to interfere with the light thrown out from the rod.

A further modification of the invention is illustrated in Fig. 13 in which two relatively small diameter coils 92 and 93 are mounted in parallel relation to two coils 94 and 95. Support rods 96, 97, 98, and 99 sealed in the press 100 support respectively the coils 94, 92, 93, and 95. A center support rod 101 may be sealed in the press 100 and may be provided with a glass bead 102 at the upper end thereof in which is sealed a connector 103 which supports and electrically connects the upper ends of the coils 94 and 93. A second connector 104 may be welded to the support rod 101 and may connect the upper end of the coils 92 and 95. Leading-in wires 104 and 105 may be connected to the support rods 96 and 99 respectively while leading-in wires 106 and

107 may be connected respectively to the support rods 97 and 98. These latter leading-in wires 106 and 107, may be connected together and when so constructed current will flow, in operation, through the leading-in wire 104, the support rod 96, the large diameter coil 94, the connector 103, the small diameter coil 93, the support rod 98, the leading in wire 107, the leading in wire 106, the support rod 97, the small diameter coil 92, the connector 104, the large diameter coil 95, the support rod 99, and out through the leading-in wire 105. At the center of each of the coils 92 and 93 I provide, respectively, electron emitting coatings 108 and 109 which may extend a portion of the length and are preferably provided at the center or away from the support rods to prevent arcing across the high potential rods. Current flowing through the coils as mentioned raises the temperature of the fine wire coils 92 and 93 to a greater temperature than the outer coil. The electron emitting material tends to emit electrons when the temperature becomes high enough and, inasmuch as the larger diameter coils 94 and 95 having a relatively large difference in potential from the smaller diameter coils, electrons will bombard the outer coils from the small coils. Bombardment of the outer coils raises the temperature thereof to incandescence and causes the outer coils to emit light with an intense illumination.

If desired the coils shown in Fig. 13 may be made to extend at angles to each other instead of being parallel so that the point of bombardment will be more or less confined and no tendency is found to spread the bombardment throughout the length of the filament or to overheat the filaments at the high potential ends.

In any of the constructions shown it is obvious that several elements may be provided either connected in series or in parallel and these elements may be positioned in any desirable manner within the envelope. Also while I have specifically referred to an ionized gas within the envelope it may be preferred to operate some of the modifications of the invention with traces of the metal vapors such as mentioned above and it may also be desired to operate some of the constructions in a vacuum and I do not therefore desire to be limited to the use of an ionized gas. I have also referred to certain specific pressures for the gases but it is to be understood that where a gas is used the pressure may be varied depending on the character of the discharge desired and the voltage used. Lowering the pressure tends to cause the discharge around the emitting element to expand.

Many other modifications of the invention may be resorted to without departing from the spirit thereof, and I not therefore desire to limit myself to what has been shown and described except as such limitations occur in the appended claims.

What I desire to claim and secure by Letters Patent is:

1. In an electric lighting device a tubular cathode, a coil of refractory wire around said cathode and spaced therefrom, electron emitting material in surface contact with said cathode, means to heat said cathode, means to give said coil a different potential from said cathode when a current is applied to said device, and an ionizable gas surrounding said coil and cathode.

2. A lamp comprising an envelope, an electron emitting element within said envelope, an anode spaced slightly from said element and connected

in simple series therewith, and an ionizable gas surrounding said element and anode.

3. An electric lamp comprising an envelope, a coil of filamentary resistance wire within said envelope, means to give said coil a high electron emissivity when said coil is energized by a current of electricity, a second coil adjacent the first coil but spaced therefrom, means to connect said second coil in series with said first coil, and an ionizable gas surrounding said coil.

4. An electric lamp comprising an envelope, a coil of filamentary resistance wire within said envelope, a second coil of refractory wire surrounding said first coil, a coating of electron emitting material on said first coil to render said first coil electron emitting when a current of electricity is run therethrough, means to connect said coils in series, and an ionizable gas surrounding said coils.

5. A negative glow lamp of the gaseous conduction type comprising an enclosing envelope, a plurality of thermionically active electrodes therein and a grid located between said electrodes.

6. A negative glow lamp of the gaseous conduction type comprising an enclosing envelope, a plurality of thermionically active electrodes therein, a perforated grid located between said electrodes, said grid being in parallel electrical relationship with one of said electrodes.

7. An ultraviolet lamp comprising an enclosing envelope, an ionizable medium therein, said envelope having a press, a plurality of electrodes supported by said press, each of said electrodes including a heating element and a thermionically active material, the heating elements of said electrodes being in electrical series relationship, and a grid located in the space between said electrodes.

8. An ultraviolet lamp comprising an envelope, an ionizable medium therein, a plurality of thermionic electrodes and a grid also located therein, said electrodes being spaced from each other and supported by a press, said grid being located in the space between said electrodes, each of said electrodes including a hollow body having a thermionically active surface and a heater element, said heater elements being connected in electrical series relationship, said grid also being supported by said press.

9. An ultraviolet lamp comprising an enclosing envelope, an ionizable medium, a plurality of electrodes and a grid located therein, said electrodes being spaced from each other and supported by a press, each of said electrodes including a heater element and a thermionically active material, a grid located in the space between said electrodes, said grid being in electrical parallel relationship with one of said electrodes.

10. A direct current electric cathode-glow lamp, comprising a translucent bulb, a filling in said bulb consisting mainly of at least one rare gas, a metal cathode in said bulb having a coating of the alkaline earth type, a resistance type heater for said cathode, means for energizing said heater, a wire anode in said bulb bent substantially into a helix surrounding and symmetrically disposed with respect to the cathode and at a uniform distance from the latter and means for applying a potential difference between the two electrodes, said anode having a small total surface area with respect to the cathode area.

11. A negative glow lamp of the gaseous conduction type comprising an enclosing envelope,

a plurality of electrodes therein, a grid surrounding and spaced from each of said electrodes, each of said grids being in parallel electrical relationship with the electrodes surrounded thereby.

12. A gaseous conduction lamp comprising an enclosing envelope, an ionizable medium therein, said envelope having a press, a plurality of electrodes supported by said press each of said electrodes including a heating element and a thermionically active material, the heating elements of said electrodes being in electrical series relationship, and a grid located in the space between said electrodes.

13. A gaseous conduction lamp comprising an envelope, an ionizable medium therein, a plurality of thermionic electrodes and a grid also located therein, said electrodes being spaced from each other and supported by a press, said grid being located in the space between said electrodes, each of said electrodes including a hollow body having a thermionically active surface and a heater element, said heater elements being connected in electrical series relationship, said grid also being supported by said press.

14. A gaseous conduction lamp comprising an enclosing envelope, an ionizable medium therein, said envelope having a press, a plurality of electrodes supported by said press each of said electrodes including a heating element and a thermionically active material, the heating elements of said electrodes being in electrical series relationship, and a plurality of apertured electrically conducting cylindrical grid elements completely surrounding said electrodes respectively.

15. A gaseous conduction lamp comprising an envelope, an ionizable medium therein, a plurality of thermionic electrodes and a grid also located therein, said grid being formed as an apertured electrically conducting cylindrical element and completely surrounding at least one of said electrodes, said electrodes being spaced from each other and supported by a press, said grid being located in the space between said electrodes, each of said electrodes including a hollow body having a thermionically active surface and a heater element, said heater elements being connected in electrical series relationship, said grid also being supported by said press.

16. In an electric lighting device, dual tubular cathodes, a two-sectioned heater for said cathodes, each section of the heater being positioned within one of the cathodes and electrically insulated therefrom, means to connect the midpoint of the heater to one of said cathodes, a pair of anodes spaced from said cathodes, one of said anodes being connected to one end of said heater and the other anode being connected to the other end of the heater, and an ionizable gas surrounding the anodes, cathodes and heater.

17. In an electric lighting device a cathode, a coil of refractory wire adjacent said cathode and spaced therefrom, means to heat said cathode to electron emitting temperature, means to give said coil a different potential from the cathode when a current is applied to said device, and an ionizable gas surrounding said coil and cathode.

CHESTER H. BRASELTON.
